GOLF BALL TESTING MACHINE

Raphael Atti, Cliffside Park, N. J.

Application June 11, 1940, Serial No. 339,839

3 Claims. (Cl. 265—19)

This invention relates to machines for testing the hardness of material in general and more especially to machines for testing the hardness of golf balls or their resistance to pressure.

It has long been recognized that within certain limitations, the value of a golf ball is mainly determined by the hardness of the same or its resistance to pressure. Furthermore, unless extreme care is exercised in the method or manufacture and the selection of materials used, it is very difficult to manufacture a batch of golf balls of equal hardness or equal resistance to pressure within predetermined limits. Still furthermore, the components of a golf ball, rubber components as an instance, will deteriorate with time whether the golf ball is used or not resulting in a change of hardness of the ball and consequent change in its quality. Consequently the need has arisen, especially at golf tournaments that some means be provided for quickly testing the golf balls to be played in a tournament on the field preparatory to play so that the players in the tournament may be assured of balls measuring up to a predetermined standard, such for instance as the tournament standard extensively adopted in the United States. In view of the foregoing, it is an object of the present invention to provide an improved portable machine which can with facility be set up on the field or wherever desired to test the golf balls to be used preparatory to play, at least as to their hardness or their resistance to pressure.

These and other features, capabilities and advantages of the invention will appear from the subjoined detailed description of one specific embodiment thereof illustrated in the accompanying drawing in which

Figure 1 is a front elevation partly in section of this testing machine;

Fig. 2 is a side elevation of a machine partly in section on a smaller scale than that shown in Fig. 1; and

Fig. 3 is a transverse section on the line 3—3 of Fig. 1.

In the embodiment shown, there is provided a base 1 from which two arms 2 and 3 extend upwardly and terminate in the vertically extending cylindrical chambered portion 4. The arms 2 and 3 are provided with the journal bosses 5 and 6 in alinement with one another to receive the shaft 7 which is keyed to the slotted drum 8 having a pin 9 eccentrically connecting the link 10 thereto to oscillate in the slot, which link 10 is pivotally connected to the pin 11 extending

through the plunger 12 slidably mounted in the chambered portion 4.

As shown, the link 10 engages the pin 11 substantially centrally of the cylinder 12, the slot 13 being provided in the plunger 12 to receive the link 10. At the upper end of the chambered portion 4 and preferably projecting from opposite sides thereof, there are provided the two extensions 14 and 15 provided with vertically extending openings to receive the diminished screw threaded portions 16, 17, respectively extending down from the posts 18 and 19 respectively.

The portions 16 and 17 are long enough to protrude from the lower end of the extensions 14 and 15 and there receive the nuts 20 and 21 respectively to anchor the posts 18 and 19 to the extensions 14 and 15. The upper ends of the posts 18 and 19 are also provided with diminished screw threaded portions 22 and 23 respectively which extend through the extensions 24 and 25 respectively of the bracket 26.

The portions 22 and 23 are long enough to extend through the extensions 24 and 25 and receive at their upper ends the nuts 27 and 28 respectively. The nut 27 is screwed down tightly against the upper face of the extension 24 to lock the bracket 26 and post 18 together. Between the nut 28 and the extension 25, there is preferably provided, as here shown, a stop finger 29. Consequently when the nut 28 is screwed down into place, it will not only anchor the bracket 26 and post 19 to one another but also serve to fix the stop finger 29 in place.

The bracket 26 preferably has a cylindrical chamber 30 to receive the cylindrical head 31 connected to the lower end of the stem 32 which extends through the plate 33 secured to the upper end of the bracket 26. In order to limit the downward movement of the stem, thereby also the downward movement of the cylindrical head 31, the upper end of the stem 32 is provided with a head or disc 34.

In the present instance above the disc 34, there is formed a polygonal shaped extension 35. Between the plate 33 and the cylindrical head 31, there is positioned a spring 36 of standard construction. In the present instance, the spring shown is square in cross-section. Preferably also the disc 34 and head 31 are so positioned that the spring is under tension when positioned between the two.

Above the plate 33, there is positioned the inverted cup-shaped frame 37 having flange 38 to receive the screws 40 passing through the disc 33 and in screw threaded engagement with the

upper portion 43 of the bracket 26 thereby not only to anchor the frame 37 in position but also to anchor the disc 33 to the bracket 26 and thereby confine the spring 36 to movement in the chamber 30.

The upper portion 44 of the frame 37 is preferably provided with a vertically extended cylindrical chamber to receive the neck 45 extending down from the dial housing 46 of the indicating mechanism. The portion 44 is preferably split or provided with a division with the ears 47 and 48 extending laterally therefrom as shown in Fig. 2 to receive the clamp screw 49 to press the split portions together and thereby securely anchor the neck 45 in place. Operatively connected to the indicating mechanism in the dial housing 46, there is provided the stem 51 slidably mounted in the neck 45.

The article, as an instance the golf ball 52 of which the hardness is to be measured is preferably centered on the upper plane face of the plunger 12 by the mat 53 preferably composed of some suitable yieldable substance, such as rubber, and provided with a central opening large enough so that the ball 52 will freely engage the upper face of the plunger 12 when so positioned. The lower face of the head 31 likewise is preferably plane as shown so that, there will be a one point contact both between the ball 52 and the head 31 and between the ball 52 and plunger 12.

In the operation of the testing machine after the ball 52 is centered by the mat 53 relative to the plunger 12, the handle 54 which is pinned to the shaft 7 is swung upwardly until it engages the stop arm 29 which is so positioned that in this position of the arm 54, the link 10 will be substantially vertical where the ball 52 will have engaged the head 31 and have raised the head 31 a distance corresponding to the degree of hardness of the ball. In other words, it will require a pressure of two hundred pounds after the ball engages the head 31 in order to start compressing the spring 36 and to compress the spring the distance corresponding to the distance between the upper face of the head 31 shown in Fig. 1 and the lower end of the stem 51 will require another one hundred pounds.

From the foregoing, it will thus be seen that before the indicator registers, the ball will have to withstand at least a pressure of three hundred pounds. If the ball 52 collapses too readily to enable the stem 51 to be raised, it will mean that the ball 52 will collapse for a predetermined distance at least equal or greater than the normal distance between the lower end of the stem 51 and the upper face of the head 31 with a pressure of three hundred pounds or less. If, on the other hand, the degree of hardness is such that it will require more than a pressure of three hundred pounds to collapse the ball a predetermined distance, according to the present machine, the stem 51 will then be raised to actuate the indicating mechanism to indicate pressures greater than three hundred pounds.

As an instance, it has been determined that with a golf ball of the present standard diameter of 1.68 inches where the distance at the highest position of the plunger 12 between the upper face of the plunger 12 and the lower face of the head 31 without any movement of the head 31 is 1.375 inches, then a pressure of three hundred and ten pounds or less would determine the type of ball that is today in a class worth twenty-five cents or less per piece and in turn when the pressure indicated is more than three hundred and

ten pounds and less than three hundred and thirty pounds, the ball being tested will be in a class today worth thirty-five cents or less per piece. When the pressure indicated is between 5 three hundred and thirty pounds and three hundred and fifty pounds, the ball being tested will be in the class worth fifty cents or less per piece. When the pressure is between three hundred and 10 fifty pounds and three hundred and seventy pounds, then the ball being tested will be in the class worth seventy-five cents or less which is 15 today known as the durable type of ball and when the pressure indicated is over three hundred and seventy pounds, then the ball being tested will be in the tournament class.

To facilitate reading the pressures and thereby facilitate classifying the balls being tested, it is contemplated as shown in Fig. 1 that the zone on the dial of the housing 46 between zero and 10 pounds will be colored white, the zone between 10 pounds and 30 pounds will be colored orange, the zone between 30 pounds and 50 pounds will be colored green, the zone between fifty pounds and seventy pounds will be colored blue, the zone 25 between seventy pounds and ninety pounds will be colored red and the zone between ninety pounds and back to zero, will also be colored white.

It is obvious that various changes and modifications 30 may be made to the details of construction without departing from the general spirit of the invention as set forth in the appended claims.

I claim:

1. The combination of a base having an upwardly extending bracket portion, a bracket, means for connecting said bracket portion and bracket to one another but spaced from one another a distance exceeding the diameter of the 40 type of golf ball to be tested, said means connecting diametrically opposite upper ends of said bracket portion to diametrically opposite lower ends of said bracket, said bracket portion and bracket having elongated aligned cylindrical openings, an elongated cylindrical plunger conforming to the cylindrical opening in said bracket portion, to be guided by, and movably mounted in, the cylindrical opening of said bracket portion and provided with an upper golf ball receiving face, a shaft extending through said bracket portion below its cylindrical opening, an eccentric on said shaft, a link connecting said eccentric to the central lower portion of said plunger, a lever fixed to said shaft, a cylindrical head conforming to the cylindrical opening in said bracket 50 portion to be guided by, and movably mounted in, the cylindrical opening in said bracket, an abutment at the upper end of said bracket, a guide rod slidably mounted in said abutment and extending down and connected to said head, a stop at the upper end of said guide rod slidably to anchor said head and guide rod in said bracket, a spring interposed between said abutment and said head, and a hardness registering indicator mounted at the upper end of said bracket and having a hardness sensing stem in the path of movement of said stop to cooperate with said spring in turn to indicate the hardness of the golf ball to be tested.

2. The combination of a base having an upwardly extending bracket portion, a bracket, means for connecting said bracket portion and bracket to one another but spaced from one another a distance exceeding the diameter of the 70 type of golf ball to be tested, said means con-

necting diametrically opposite upper ends of said bracket portion to diametrically opposite lower ends of said bracket, said bracket portion and bracket having elongated aligned cylindrical openings, an elongated cylindrical plunger conforming to the cylindrical opening in said bracket portion, to be guided by, and movably mounted in, the cylindrical opening of said bracket portion and provided with an upper golf ball receiving face, a shaft extending through said bracket portion below its cylindrical opening, an eccentric on said shaft, a link connecting said eccentric to the central lower portion of said plunger, a lever fixed to said shaft, a cylindrical head conforming to the cylindrical opening in said bracket to be guided by, and movably mounted in, the cylindrical opening in said bracket, an abutment at the upper end of said bracket, a guide rod slidably mounted in said abutment and extending down and connected to said head, a stop at the upper end of said guide rod slidably to anchor said head and guide rod in said bracket, a spring interposed between said abutment and said head, and a hardness registering indicator mounted at the upper end of said bracket and having a hardness sensing stem in the path of movement of said stop to cooperate with said spring in turn to indicate the hardness of the golf ball to be tested, and a yieldable annular seat on the upper golf ball receiving face of said plunger, said golf ball receiving face being normally disposed below the upper end of said cylindrical opening in said bracket portion to cooperate with the yieldable annular seat in centering the golf ball to be tested.

3. The combination of a base having an upwardly extending bracket portion, a bracket, means for connecting said bracket portion and

5 bracket to one another but spaced from one another a distance exceeding the diameter of the type of golf ball to be tested, said means connecting diametrically opposite upper ends of said bracket portion to diametrically opposite lower ends of said bracket, said bracket portion and bracket having elongated aligned cylindrical openings, an elongated cylindrical plunger conforming to the cylindrical opening in said bracket portion, to be guided by, and movably mounted in, the cylindrical opening of said bracket portion and provided with an upper golf ball receiving face, a shaft extending through said bracket portion below its cylindrical opening, an eccentric on said shaft, a link connecting said eccentric to the central lower portion of said plunger, a lever fixed to said shaft, a cylindrical head conforming to the cylindrical opening in said bracket to be guided by, and movably mounted in, the cylindrical opening in said bracket, an abutment at the upper end of said bracket, a guide rod slidably mounted in said abutment and extending down and connected to said head, a stop at the upper end of said guide rod slidably to anchor said head and guide rod in said bracket, a spring interposed between said abutment and said head, and a hardness registering indicator mounted at the upper end of said bracket and having a hardness sensing stem in the path of movement of said stop to cooperate with said spring in turn to indicate the hardness of the golf ball to be tested, said head normally extending below the lower level of said bracket so that the lower face of said bracket will at all times clear the golf ball to be tested during the testing operation.

RAPHAEL ATTI.
